UNITED STATES PATENT OFFICE

140,398

DESIGN FOR A LADY'S HAT OR THE LIKE

Hans Herrmann, Chicago, Ill.

Application September 26, 1944, Serial No. 115,466

Term of patent 3½ years

(Cl. D3—13)

To all whom it may concern:

Be it known that I, Hans Herrmann, a citizen of the United States, residing at Chicago, in the county of Cook and State of Illinois, have invented a new, original, and ornamental Design for Lady's Hat or the like, of which the following is a specification, reference being had to the accompanying drawings, forming part thereof.

Fig. 1 is a perspective view of a lady's hat showing my new design.

Fig. 2 is a front view of same.

Fig. 3 is a rear view of same.

I claim:

The ornamental design for a lady's hat or the like, as shown.

HANS HERRMANN.
